(57) **CLAIM**

The ornamental design for a display screen with graphical user interface for an account identifier, as shown and described.

DESCRIPTION

FIG. 1 is a front view of a first embodiment of a display screen with graphical user interface for an account identifier showing our new design;

FIG. 2 is a front view of a second embodiment of a display screen with graphical user interface for an account identifier showing our new design;

FIG. 3 is a front view of a third embodiment of a display screen with graphical user interface for an account identifier showing our new design;

FIG. 4 is a front view of a fourth embodiment of a display screen with graphical user interface for an account identifier showing our new design;

FIG. 5 is a front view of a fifth embodiment of a display screen with graphical user interface for an account identifier showing our new design; and,

FIG. 6 is a front view of a sixth embodiment of a display screen with graphical user interface for an account identifier showing our new design.

The broken lines of certain numbers and the broken lines of the surrounding boxes in the drawings form no part of the claimed design.

1 Claim, 6 Drawing Sheets
